UNITED STATES PATENT OFFICE.

SEBASTIAN ZIANI DE FERRANTI, OF HOLLINWOOD, ENGLAND, ASSIGNOR TO FERRANTI, LIMITED, OF HOLLINWOOD, ENGLAND.

ROTOR OF MERCURY BATH ELECTRICITY METERS.

Application filed April 14, 1925, Serial No. 23,120, and in Great Britain June 19, 1924.

This invention relates to disc rotors of mercury bath electricity meters, which rotors are protected from amalgamation with mercury by a metallic coating applied thereto.

5 It is necessary to remove air from beneath the rotor disc after the latter is immersed in the mercury within the bath and it is usual to drill or punch a plurality of holes near the spindle collet to enable this air to escape or to 10 be withdrawn.

I find it necessary as far as possible to guard against the possibility of failure of the protective coating due to the presence of these holes and due to the usual methods of fixing 15 the spindle collet.

Accordingly I form in the disc a single central aperture in lieu of the plurality of holes adjacent the spindle collet, this aperture being rounded at both ends so as to produce an 20 inner periphery which is convex in any plane containing the longitudinal axis of the disc and I form a collet as a spider which is suitably shaped in order not to damage the coating within the central hole.

25 Again, I find it desirable slightly to taper the disc both near its outer periphery and near its central hole so that when the disc is subjected to a hammering or pressing (in order to harden and render it compact) the edges 30 are left intact, the coating thus being unimpaired.

Referring to the accompanying diagrammatic drawings:—

Figures 1 and 2 represent cross-sectional 35 views of a disc rotor in two stages of treatment in accordance with the present invention;

Figure 3 is a section on the line A—A of Figure 4 and represents the disc mounted on 40 the spindle in a convenient manner in accordance with the present invention;

Figure 4 is a plan view corresponding to Figure 3, and

45 Figure 5 is a sectional view through B—B of Figure 4.

In carrying the invention into effect according to one example in accordance with the present invention as illustrated in Figures 1—5, I provide a metal disc *a*, say of copper, with a central aperture and annular tapered surfaces *b b*, *c c* adjacent this aperture and

adjacent the periphery respectively. This disc is coated with a metallic coating and is then pressed between parallel surfaces so as to harden the metal and to planish the protective coating. Alternatively, I may interpose a layer of resilient material, such as vulcanized rubber, between one of said surfaces and the disc, afterwards reversing the disc and repeating the pressing operation.

The disc now assumes approximately the cross-section indicated in Figure 2. The collet comprises conveniently a spider *d* with four spokes, this being inserted within the aperture in the disc and pressed over at *e* (Figure 3) so that the surfaces *f f* are forced 65 outwards and so firmly clamp the collet to the disc without, however, damaging the surface *g* at the aperture of the disc.

The collet is screwed to the spindle *j* at *h* as indicated and it will be appreciated that the spaces *k* between the spokes provide openings through which air may escape during the filling of the mercury bath with mercury.

I prefer to construct the collet spider of substantially non-magnetic iron or steel which thus does not become amalgamated in the mercury bath.

Having now described my invention, what I claim as new and desire to secure by Letters Patent is:—

1. A method of forming the disc rotors of mercury bath electricity meters which consists in providing a metal disc at its centre with an aperture and adjacent such aperture and adjacent the periphery providing it with tapered surfaces, applying a metal protective coating to said disc and applying pressure to said disc, thereby hardening it and planishing its surface and incidentally rendering its thickness substantially uniform throughout.

2. A mounting for the disc rotor of an electricity meter including a spindle, a collet rigid therewith, a disc-like annulus, the inner periphery of which is convex in any plane containing the longitudinal axis of the annulus, and a plurality of spokes embodied in said collet, the outer surfaces of which spokes are concave in cross section to correspond with the said convex inner annulus periphery when clinched into position within the annulus.

3. A mounting for the disc rotor of an

electricity meter including a spindle, a collet screwed to said spindle, a disc-like annulus, the inner periphery of which is convex in any plane containing the longitudinal axis of the annulus, and a plurality of spokes embodied in said collet, the outer surfaces of which spokes are concave in cross section to corre-

spond with the said convex inner annulus periphery when clinched into position within the annulus.

In testimony whereof I have signed my name to this specification.

SEBASTIAN ZIANI DE FERRANTI.
